CLAIM

The ornamental design for a visor bonnet, as shown and described.

DESCRIPTION

FIG. 1 is a perspective view of a visor bonnet showing our new design.

FIG. 2 is a front view thereof.

FIG. 3 is a rear side view thereof.

FIG. 4 is a left side view thereof.

FIG. 5 is a right side view thereof.

FIG. 6 is a top plan view thereof; and,

FIG. 7 is a bottom plan view thereof.

The broken lines are used to illustrate features of the article which form no part of the claimed design.
